DESIGN FOR A TOY ANIMAL

Frederick R. Frederick and Adolph Arthur Frederick, Crestwood, N. Y., assignors to Ruth M. Harkness, New York, N. Y.

Application February 2, 1937, Serial No. 67,407

Term of patent 14 years

To all whom it may concern:

Be it known that we, Frederick R. Frederick and Adolph Arthur Frederick, both citizens of the United States and residents of Crestwood, in the county of Westchester, State of New York, have invented a new, original, and ornamental Design for a Toy Animal, of which the following is a specification, reference being had to the accompanying drawing, forming part thereof.

The accompanying drawing shows in Figure 1 a side elevation, in Figure 2 a plan view, and in Figure 3 a front elevation, of a toy animal showing our new design.

We claim:

The ornamental design for a toy animal, substantially as shown.

FREDERICK R. FREDERICK.
A. ARTHUR FREDERICK.
